UNITED STATES PATENT OFFICE.

JOSEPH C. NUVER, OF ALLENTEWON, PENNSYLVANIA, ASSIGNOR TO I. A. HALL & COMPANY,
OF PATERSON, NEW JERSEY, A FIRM.

SHUTTLE.

No. 906,455.

Specification of Letters Patent.

Patented Dec. 8, 1908.

Application filed November 14, 1907. Serial No. 402,093.

To all whom it may concern:

Be it known that I, JOSEPH C. NUVER, a citizen of the United States, residing in Allentown, Lehigh county, Pennsylvania, have invented certain new and useful Improvements in Shuttles; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My present invention relates to shuttles for looms and it consists in certain improvements in the means for mounting the spindles whereby a more substantial, durable and practical shuttle is produced. As commonly constructed, the mounting for the spindle of a loom shuttle involves the use of several pins which are driven through the walls of the shuttle horizontally and coöperate with a bent steel spring to hold the spindle in its proper elevated or depressed position. It is well known that these pins operate sooner or later in many cases to cause the wood of the shuttle to split; besides, they are likely to work loose laterally, and by projecting effect damage to the reed and other parts of the loom. Again, the spring referred to occasionally breaks and falling into the warp produces a "smash". These several disadvantages are of course all attended with loss of time and labor in the making of repairs and in keeping the shuttles in proper working condition.

My present invention has for its object to provide a mounting for the spindles of shuttles whereby the several disadvantages above pointed out as existing in the use of the mountings for shuttle spindles now commonly employed will be entirely overcome.

A still further object of my invention is to provide means whereby the spindle may be adjusted with reference to the longitudinal axis of the shuttle when the spindle is depressed, thus making it unnecessary for the weaver to resort to the usual expedient of pressing down on the free end of the spindle in order to effect the adjustment, which action, as is well known, often has for its effect to split the wood of the shuttle.

My invention is fully illustrated in the accompanying drawings, wherein, Figure 1 is

a top plan view of the improved shuttle; Fig. 2 is a side view thereof, a portion of the near wall of the shuttle being broken away to show its internal construction; Fig. 3 is a plan view of the spindle and its mounting removed from the shuttle; Fig. 4 is a transverse sectional view in the axis of the screw which holds the mounting in place; Fig. 5 is a plan view of the blank from which the box or casing of the mounting is produced; Fig. 6 is a longitudinal sectional view of a modified form of such box or casing; Fig. 7 is a plan view of the blank from which the box or casing of Fig. 6 is produced; Fig. 8 is a plan view of the improved shuttle with a modified form of means for securing its spindle mounting in place; and, Figs. 9, 10 and 11 are, respectively, a side view (partly in section), a transverse sectional view, and a view of a detail of the shuttle shown in Fig. 8.

In said drawings, *a* designates the shuttle body having the usual bobbin cavity *b*; *c* is a longitudinal extension of said cavity, the same being formed open at the top, as seen in Fig. 1 but having an overhang or flange *d*. In the socket thus formed by the extension *c* of the cavity *b* is arranged the box or casing *e* of the mounting for the spindle *f*. In order to form this box or casing, a blank *g* like that shown in Fig. 5 is first cut out of sheet metal, whereupon the portions *h* of said blank are turned up parallel to each other on the lines *i*; subsequently the left hand ends of the portions *h* are bent around the curved rear edge *j* of the portion *h* of the blank which forms the bottom of the box or casing, while the right hand ends of said portions *h* are bent to form the jaws *l* which serve to hold the bobbin or quill in proper position on the spindle when the spindle is depressed. Before shaping the blank to give it the form of the box or casing, it has three pairs of holes *m*, *n* and *o* punched in its portions *h*, and when the latter are bent up to form the side walls of the box or casing the holes of each pair are opposed to each other.

The openings *m* and *o* receive the riveted pins *p* and *q*, the same acting partly to give stoutness and strength to the box and partly to support the spindle *f* and the plate-spring *r*, said spindle having its butt *s* fulcrumed on the pin *q* and the spring *r* having its end *t* passed around the pin *p* under the same

and bearing against the bottom of the box or casing and its other end *u* engaging under the butt of the spindle. In forming the blank, it is provided in its portions *k* with 5 an opening *v* which is designed to allow the downward play of the end *u* of the spring *r* when the spindle is elevated.

The box or casing, carrying the spindle and spring, as just described, is fitted into 10 the socket formed by the extension *c* of the cavity *b* by placing the parts in the cavity and then forcing the casing back into the socket, which it snugly fits, as shown in the drawings. In this position it is held against 15 movement by the screw *w* which is driven through the sides of the shuttle and the holes *n* of the box or casing. The bottom of the extension *c* of the cavity is formed with a recess *x* opposite the opening *v* of the 20 box or casing so as to allow spring *r* to have full play downwardly when the spindle is elevated.

In the modification shown in Figs. 6 and 25 7, in addition to the side jaws for holding the bobbin or quill in place on the spindle a third jaw *y* may be cut out in the blank from the portion of the metal standing between that forming the side jaws *z*, the jaw *y* being then merely given the necessary 30 hook-shape, as shown in Fig. 6, so that, when the box or casing has been completed from the blank and the jaw *z* correspondingly shaped, the relation of the jaws *y*, *z* and *z* will be such that they will engage the 35 bobbin or quill at three sides thereof.

In order to make it possible to secure the proper positioning of the spindle when depressed, I provide a screw 1 in its butt so arranged that, when properly adjusted by a 40 screw-driver, its head 2 will bear against some fixed part of the shuttle structure, as the bottom wall of the box or casing. This screw may be conveniently reached by a screw-driver for the purpose of adjusting it, 45 and introduced according to the arrow in Fig. 2, whenever the spindle is elevated.

In place of employing a screw to secure the box or casing in its socket in the shuttle I find the construction shown in Figs. 8 to 50 11 in many cases preferable; opposed vertical grooves 3 are cut in the sides of the socket formed by the extension *c* of the quill cavity and into these is driven a staple 4 which fits snugly in its place in the grooves and is 55 adapted to have its horizontal portion 5 (when the staple is driven fully home and the box or casing is in place in the socket) enter the recesses 6 in the top edges of the sides of the box or casing. The box or casing can not now be removed without first 60 raising the staple slightly, which may be accomplished by prying it up. This construction, wherein the parts marked 3 and 6 form recesses open each transversely with 65 respect to the axis of the portion of the se-

curing device 4 directly received thereby, renders it even more unlikely for the shuttle to split, because no holes which would weaken it along the grain of the wood are necessary; it also avoids entirely the use of 70 parts which might work loose from the side of the shuttle to effect damage as hereinbefore indicated.

It will be apparent that in any of the forms of my improved shuttle, should the 75 spring *r* break, as occasionally happens, the pieces thereof will not fall down from the shuttle to cause a "smash", but will be held in the box or casing until the shuttle is removed from the loom.

Having thus fully described my invention, what I claim and desire to secure by Letters Patent is:

1. The combination of the shuttle body, a spindle, a mounting for the spindle removably arranged in the shuttle body, and a device for securing the mounting in the shuttle body, said shuttle body and mounting having recesses to receive the securing device, one of said recesses being open transversely with respect to the axis of the portion of said device received thereby, substantially as described.

2. The combination of the shuttle body having a socket forming an extension of its 95 quill cavity, a spindle, a mounting for the spindle removably arranged in the socket, said socket being accessible to the mounting from the quill cavity and limiting the movement of the mounting when introduced there- 100 in in directions transverse of the shuttle, and a staple interlocking the mounting with the shuttle against movements lengthwise of the shuttle, substantially as described.

3. The combination of the shuttle body 105 having a socket, a spindle, a mounting for the spindle arranged in said socket, and a staple straddling the mounting and interlocking the same with the shuttle body, substantially as described.

4. The combination of the shuttle body having a cavity therein and grooves formed in opposing surfaces of said cavity, a spindle, a mounting for the spindle removably arranged in said cavity in the grooved portion thereof, said mounting being recessed, and a staple straddling the mounting and engaging in said grooves in the shuttle body and in the recesses of the mounting, substantially as described.

5. The combination of the shuttle body, a spindle, a mounting for the spindle removably arranged in the shuttle body, and a staple straddling the mounting and interlocking the mounting with the shuttle body, 125 said mounting and the shuttle body being recessed to receive the staple, substantially as described.

6. The combination of the shuttle body, the spindle, a mounting for the spindle con- 130

sisting of a box or casing comprising two side walls and a bottom wall, said bottom wall having an opening therein, pins connecting the side walls of the mounting and 5 one of them forming a bearing for the spindle, a bent spring extending around the other pin and having one end bearing against the bottom wall of the mounting back of the opening therein and the other end extending 10 forward and engaging the butt of the spindle, and an adjusting screw arranged in the under side of the butt of the spindle and

adapted to bear against the bottom wall of the mounting forward of said opening therein, said opening being arranged under the 15 engaging portions of the spring and spindle butt, substantially as described.

In testimony, that I claim the foregoing, I have hereunto set my hand this 9th day of November, 1907.

JOSEPH C. NUVER.
